ELECTRICAL DECODING AND WORK
ACTUATING APPARATUS

Harmon G. Shively, Akron, Ohio, assignor to The B. F. Goodrich Company, New York, N. Y., a corporation of New York

Application September 28, 1956, Serial No. 612,862

5 Claims. (Cl. 317—149)

This invention relates to electrical means for controlling the operation of machinery automatically from a coded signal device such as a punched tape. As an example of the use of the device of this invention, automatic tire building machines are now in operation, which machines have a relatively large number of work stations each of which requires properly timed operation of motors, valves, and the like at such stations. Prior control devices have incorporated a series of cams for control, which cams must be specially cut and synchronized in order to effect the desired control. As an example of one means to practice the invention, the use of a punched tape and an electronic decoding device will be explained which system replaces the aforesaid cams thereby making modifications in the programming of the machine and variations in the cycling of the operations readily attainable without the need for cutting new cams and adjusting them. Proposals have been made for decoding punched cards and tape wherein the sensing elements and their relays are cascaded, that is, the first bank will be a single dual sensing element that directs a signal to one of two dual elements in the second bank, the number of elements of each succeeding bank being doubled so that depending upon the code the signal takes a devious or shunted path from bank to bank. This means that the number of elements in each bank progressively increases and if these elements involve electron tubes the maximum voltage drop from the cathode of the tube in the first bank to the plates of the tubes in the final bank can become very high, rendering the circuits critical. The use of electron tubes, however, for the basic control is desirable in that they draw small current and are instantaneous in operation, thereby making available very small steps or increments of time for the minimum timing cycle of the apparatus.

A feature of this invention is that the pulse controlled control elements of each coding bank are all connected in parallel. Thus if vacuum tubes are employed as the pulse controlled elements, according to this invention all the control tubes of all the banks may have their plates connected in parallel to a common voltage source so that the maximum voltage drop over these tubes is only that required for operation of a single tube rather than that required for a series of tubes in cascade. The elements in the control banks are of two types, the first of which will de-energize a relay when a signal pulse is applied to the input of the element whereas it permits the relay to energize when the signal input is grounded or brought to a lower potential. The second type operates in the reverse fashion. Thus if a punched tape is used as a code signal means the control elements of the first type will de-energize the relay when a "no hole" appears under its sensing means whereas the control unit of the other type will de-energize the relay when a hole appears under its sensing means. Thus depending upon the number of control elements of each type in a given bank, and the inter-connection of the inputs of such elements, the sensing means of each bank can be arranged so that the

2

relay it controls will be energized for one and only one arrangement of holes and no holes in the tape passing under the sensing means. A detailed description of a preferred embodiment of the invention will follow a preliminary description of the basic circuit elements, and the invention will be described in detail as a system designed for decoding a tape that can be punched in closely spaced transverse rows of from no holes in a row to six holes in a row and rows occurring at uniformly spaced 10 positions along the tape.

In the drawings, Fig. 1 is a schematic drawing of the basic circuit showing a bank which has a single control element of each of the two types referred to. Fig. 2 is a schematic drawing of a six position circuit showing panels 15 being made up of pairs of control banks for energizing and de-energizing a relay. Fig. 3 shows a tape segment that would cause the first panel of Fig. 2 to first close and then open the work actuating relay of the panel.

Brief description of the circuit

The circuit of Fig. 1 illustrates the principles of a simple device made in accordance with the invention. The circuit includes a work actuating relay unit including an anode, or plate relay L₁ for controlling load A, and 25 an electron tube V₁ which forms part of the relay unit. Also in the bank is a first type of pulse control device comprising a triode electron tube V₂ and a second type comprising a pair of triode electron tubes V₃, V₄. The relay L₁ is in the plate or anode circuit of tube V₁ and 30 receives plate voltage from a voltage source B₁ which in the example is +320 volts D. C. The coil 11 of the relay attracts armature 12 causing contacts in the power line to energize the load A. In the example shown relay L₁ is normally open but closes when tube V₁ is conducting, 35 which occurs when the grid of V₁ is rendered positive with respect to its cathode. The grid of V₁ is connected to the plate source B₂, by a high value resistor R₂ which in this example has a resistance of 10 megohms.

The plates of tubes V₂ and V₄ are connected to voltage 40 source B₁ of +150 volts D. C. through a plate load resistor R₃ of 270,000 ohms in this example and the cathode of relay tube V₁ is connected to the plate load resistor R₃ at point y. The tubes used and the values of the various resistors in the circuit appear in Table 1 below.

TABLE 1

	V ₁ , V ₂ , V ₃ , V ₄	6J5, 1/2 6SN7, or equivalent
R ₂		10 meg.
R ₃		270K.
R ₄ , R ₅		1 meg.
R ₆		100K.
R ₇		680K.

55 It is noted that the plates of V₂ and V₄ are connected in parallel to the common plate resistor R₃. The voltage source B₁ is also connected by means of resistors R₄ to the input circuits for the two types of control elements, there also being grid isolating resistors R₅ in series with resistors R₄. In the first type of assembly comprising the tube V₂, R₆ leads directly to the grid of V₂. In the second type of assembly another tube V₃ is in the control or input circuit of tube V₄, and V₃ receives its plate voltage from source B₁, via R₆. A cathode bias voltage of +22 volts D. C. is supplied from source C₁ to the cathodes of V₂ and V₃ and a cathode bias voltage of +70 volts D. C. is supplied to the cathode of V₄. The grid of V₄ is not connected to B₁ as is that of V₂ but is connected through resistor R₇ to the plate of V₃.

60 Sensing switches S₁ and S₂ are connected to the input circuits of each type of control unit. When these switches are open representing a "no hole" in the tape the input

circuits are held positive with respect to the corresponding cathode by the +150 volt source B₁ through resistors R₄ and R₅. When they are closed representing a "hole" in the tape, the inputs are grounded through common ground 15 thereby lowering the bias on tubes V₂ and V₃ beyond "cut off." The grid resistors R₄ limit the current drawn from source B₁ when the switches are closed.

Operation of the pulse controlled circuit of the first type (V₂)

Assume that the V₃, V₄ unit is disconnected and that V₂ is momentarily rendered non-conducting or cut off. With control tube V₂ cut off there is no voltage drop across its plate load resistor R₃. The cathode potential of relay tube V₁ at point y in Fig. 1 is at the B₁ source voltage of +150 volts whereas the grid of V₁ at point x is made positive respect to its cathode by the B₂ source voltage of +320 volts. The grid of V₁, being positive, draws some current through R₂ so that the grid will not remain at +320 volts but will remain positive relative to the cathode of V₁. Plate current now passes through the coil 11 of relay L₁, closes contacts 12, and energizes the load A in the circuit shown in Fig. 1. Thus the relay closes when V₂ is cut off.

If V₂ is made to conduct there will be a voltage drop across its plate resistor R₃ (which is 270,000 ohms) thereby placing point x which joins the plate of V₂ and the grid of V₁ at a lower potential than that of point y and the cathode of V₁ which remain at the B₁ source potential of +150 volts. It should be remembered that R₂ connecting the grid of V₁ to the 320 volt B₂ source is of a very high resistance (10 megohms) so that once V₂ conducts, grid resistance R₂ is virtually an open circuit compared to R₃, the plate load resistance (270,000 ohms) of conducting tube V₂, hence a relatively large current will flow through R₃ and the grid of V₁ which is connected to the low potential side of R₃ will become negative relative to its cathode thereby cutting off V₁ and rendering it non-conducting. Thus the relay opens when V₂ conducts, and as mentioned, closes when V₂ is cut off.

Whether or not control tube V₂ conducts or is cut off depends upon the position of switch S₁ in its grid input circuit. If S₁ is open ("no hole") as in Fig. 1, the grid of control tube V₂, being connected to +150 volts (B₁) through resistance R₄, is made positive relative to its

45

V₁ can conduct and so energize the relay. Whether or not V₄ conducts is controlled by another tube V₃, the grid of which receives either a positive pulse signal from source B₁ through resistors R₄, R₅, or a ground input signal through resistor R₆ depending upon switch S₂. When S₂ is open, corresponding to a "no hole" part of the tape, the grid of V₃ is positive with respect to its cathode as explained in connection with tube V₂, and V₃ conducts creating a voltage drop across its plate load resistor R₆ of about 100 volts. This places point z in the grid input circuit of V₄ at about 50 volts, as compared to the +70 volts bias on the cathode of from source C₂. This cuts off V₄ so that relay tube V₁ can conduct and the relay is energized, unless other parts of the circuit are set to the contrary.

If S₂ is closed, corresponding to a "hole" in the tape, the grid of V₃ is grounded and, hence, is negative relative to the cathode which is at +22 volts bias so that V₃ is cut off. Now there is no voltage drop through the V₃ plate resistor R₆ so that point z and, hence, the grid of V₄ is made positive relative to the +70 volts cathode bias causing V₄ to conduct. The grid resistor R₇ of V₄ controls the grid current so that the grid remains sufficiently positive to keep the tube conducting without becoming positive enough to burn out the tube V₄. As mentioned, this causes a voltage drop across the common plate load resistor R₃ and places the grid of V₁ in the relay unit at a lower potential than its cathode, and V₁ is cut off and the relay de-energized. Thus the effect of the grid input switch S₂ on the V₃, V₄ unit is just the reverse of the effect of switch S₁ on the V₂ unit, in that in the V₃, V₄ unit the relay is energized with the switch open ("no hole") and de-energized when the switch is closed ("hole").

35

Operation of the units in parallel

Since the outputs or plates of the first and second type units are both connected in parallel to point x, either S₁ or S₂ can be positioned to cause V₂ or V₄, respectively, to conduct and cut off V₁ thereby de-energizing the relay, regardless of the fact that the other switch may be set to permit V₁ to conduct which would otherwise energize the relay. Thus of the four possible combinations of positions of switches S₁ and S₂ in Fig. 1 only condition 4, as given in Table 2 below, will energize the relay.

TABLE 2

	S ₁	S ₂	V ₂	V ₄	V ₁	Relay
1.....	Open....	Open....	Conducts.	Cut off....	Cut off (by V ₂)....	De-energized.
2.....	Closed...	Closed...	Cut off....	Conducts.	Cut off (By V ₄)....	Do.
3.....	Open....	Closed...	Conducts.	Conducts.	Cut off (by V ₂ and V ₄). Conducts.....	Do.
4.....	Closed...	Open....	Cut off....	Cut off....	Conducts.....	Energized.

cathode which is at +22 volts, (C₁) causing V₂ to conduct, cutting off relay tube V₁ and the relay opens. If switch S₁ is grounded ("hole"), then the grid of control tube V₂ is placed at ground potential and is therefore rendered 22 volts negative relative to the positively biased cathode of V₂. Thus under this "hole" condition, V₂ is cut off, there is no voltage drop across R₃ tending to lower V₁ grid potential and relay tube V₁ can conduct, energizing the relay.

To summarize, the V₂ type pulse controlled unit working alone would de-energize the relay with S₁ open ("no hole") and permit it to be energized with S₂ closed, ("hole").

Operation of the pulse controlled unit of the second type (V₃, V₄)

The plate of V₄ is also connected to point x leading to the common plate load resistor R₃ the point being connected both to the low potential end of plate resistor R₃ and to the grid of relay tube V₁ in the relay unit, so the effect of V₄ itself on the circuit is the same as that of V₂, namely when V₄ conducts, relay tube V₁ is cut off and when V₄ is cut off, relay tube

In the circuit of Fig. 1, the pulse input signals from the switches S₁ and S₂ can be connected in parallel with the inputs of three other pairs of control units at points a and d of Fig. 1. These units would include one unit like that of Fig. 1 with the connections to a and d crossed, a unit having two V₂ units, and a unit having two V₃, V₄ units. In the first case, condition 3 of Table 2 will operate the relay in the other composite unit and no other relay, condition 2 in the table will operate the relay in the two V₂ unit, and no other relay, and condition 1 will operate the relay in the two V₃, V₄ unit, and no other relay.

A system for a six hole tape

Fig. 2 is a schematic diagram of one panel P₁ and part of another panel P₂ designed for six hole tape operation with the parts arranged to employ a maximum number of similar panels thereby reducing the number of spare panels required for maintenance. There are first and second type pulse controlled circuits in the panels like those in Fig. 1 in that the plates of the V₂ and V₄ tubes are connected to the grid of relay tube V₁ as well

as to the common plate load resistor R_3 , which resistor in turn connects to the cathode of relay tube V_1 . The power supply and the sensing switches S_1 to S_6 are wired separately from the panel so that simple point to point connections between panels are all that are required and each panel will be like the other except for the number of V_2 or V_3 , V_4 type of units within the panel. Each panel has two banks of tubes, banks C and D. Bank C includes a work actuating relay L_2 which has one section 13 having contacts that are normally open for controlling a normally off work load A, and section 13 may have another set of contacts that are normally closed for controlling another work load B that is normally on. One or both of these arrangements may be provided as required. Relay L_2 also has a section 14 that establishes a holding circuit for the relay, as will be explained.

The sensing switches S_1 , S_2 , etc., ride on a tape T which is perforated in accordance with the control code, and when a hole appears at any switch, it is grounded through the metal backing plate 15. The tape moves in a plane perpendicular to the paper in Fig. 2. The input circuits from sensing switches S_1 to S_6 not only go to the control tubes in the two banks in the panel P_1 but the panel P_1 has bus connections a to f for connection to the input circuits in a succeeding panel, P_2 . The same applies to the input circuits of panel P_2 which connect to a third panel, etc. Several variations in panel arrangement are possible. The tubes of a control unit in each bank may be all of the first type, (V_2) all of the second type, (V_3 , V_4) or any combination of both types. Also, each of the input busses a to f may connect by suitable strapping to any one of the six input circuits of the succeeding panel as indicated by the dot-dash arrows at these connections to the right of panel P_1 .

Bank C, the work actuating bank, has its relay L_2 arranged to be self-holding. Whenever the relay L_2 is energized, a connection from the plate side of the relay coil to line 16 is made which completes a circuit through the normally closed contacts 17 of relay L_3 in bank D. As can be seen from the diagram, this completes a circuit through line 18, the power supply section B_2 , line 19, and the coil of relay L_2 , thereby holding the relay L_2 closed. However, it can be seen that when relay tube V_1 in the relay unit of bank D is energized, the normally closed holding contacts 17 of relay L_3 are opened and the circuits previously established to hold relay L_2 closed is broken so that L_2 is de-energized, assuming of course, that relay tube V_1 for relay L_2 is not conducting. Thus bank C will make or break a given load circuit A or B under one code and bank D will reverse the condition of the same load circuits under a different code.

Panel arrangements

A section of a six hole tape appears in Fig. 3. The tape is propelled intermittently by mechanisms that are known in the art by means of a line of punched holes 21. A "writer" is provided so that holes can be punched in the tape in any transverse row in lateral alignment with a drive hole 21, there being provisions for six positions in the rows corresponding to the position of switches S_1 to S_6 . These switches are actually small spring pressed rods that complete the ground circuit when they ride over a hole in the tape, the timing depending upon the service, but it being common for a cycle of one start and stop of the tape to require but a fraction of a second.

In Fig. 3 a row of holes 22 is shown wherein three "holes" appear opposite switches S_1 to S_3 and there are "no holes" opposite switches S_4 to S_6 . In bank C of panel P_1 Fig. 2, the three holes will render all of the V_2 type control units non-conducting because the grid inputs to tubes V_2 are all grounded. On the other hand, since there are no holes under sensing switches S_4 to S_6 the grid input circuits of the three V_3 trigger tubes remain positive relative to their cathodes causing all V_3 tubes to conduct

and thereby cutting off all V_4 tubes. Thus all the tubes V_2 and V_4 , connected in parallel to R_3 , are non-conducting so that the grid of relay tube V_1 may become positive relative to its cathode, and thus render tube V_1 , conducting to energize the relay L_2 . This is the only combination and arrangement of holes and no holes in the tape that will energize the relay L_2 in bank C of panel P_1 . Similarly, since bank D of panel P_1 has four V_2 type units and two V_3 , V_4 type units, only the exact arrangement of four holes 23, and two "no holes," shown in Fig. 3 to the right, will energize bank D of panel P_1 to energize relay L_3 and thus open the normally established holding circuit for relay L_2 .

It is desirable to have a minimum number of different types of panels and the combinations available with a six hole tape are as shown in Table 3.

TABLE 3

	Tube Arrangement	Number Codes Possible
3 (V_2) + 3 (V_3 , V_4)		20
4 (V_2) + 2 (V_3 , V_4)		15
2 (V_2) + 4 (V_3 , V_4)		15
5 (V_2) + 1 (V_3 , V_4)		6
1 (V_2) + 5 (V_3 , V_4)		6
6 (V_2)		1
Total		63

Each arrangement of the first and second type control units in a bank has a different number of possible combinations or codes. As shown in the table, 63 codes, each of which will cause only one arrangement of tubes in a bank to energize its relay are possible with a six hole tape. Since there is always a space between a given row of coded holes in the tape, the all blank or all "no hole" combination of six V_3 , V_4 type units is not used because in such a combination the corresponding relay could be energized each time the tape is shifted from row to row of holes.

Table 4 shows how 40 codes can be sensed with only two different types of panels, and two more different types of panels will produce 62 different codes. This arrangement reduces to three the number of types of spare panels necessary for maintenance.

Total Panels	32			Total Codes 63

The preferred embodiment (vacuum tube) form of the device can be made to respond precisely and dependably to the signals produced at the fractional second intervals typical of the tape reading machines currently available. Reference to Fig. 2 shows that since all the plates of each bank are connected in parallel across their voltage sources the total voltage difference across the entire machine need not exceed that required to operate a single tube. It makes the machine safe and not subject to break down as opposed to the cascade type of circuit. Wiring of the panels can almost be standardized and many of the panels will be alike, care only being required in the strapping of the input circuit assemblies from panel to

panel. With this circuit also the conducting or non-conducting conditions are readily made non-critical, so that despite progressive changes in circuit and tube constants dependability of operation is maintained. The filaments in each bank are preferably wired in series so that failure of one tube in a bank prevents relay operation. However, the filament wiring forms no part of this invention, is not illustrated, and can be modified in accordance with standard practice.

Having completed a detailed description of a preferred embodiment of this invention so that those skilled in the art can practice the same, I claim:

1. Electrical decoding and work actuating apparatus comprising a plurality of control banks, said banks each comprising an electrically controlled relay unit, first and second types of electric pulse-controlled devices all having their outputs connected in parallel with one another and connected to said relay unit, each pulse-controlled device having an input for receiving an electric pulse signal, means in the first type of said pulse-controlled device for supplying a de-energizing signal to said relay unit upon application of an electric pulse to the input of said device, means in the second type of said pulse-controlled devices for applying an energizing signal to said relay unit upon application of a pulse to the input of said device, said electrically controlled relay unit including means for causing a signal from any of one of said types of device to always override any opposite signals from the other type devices, regardless of how many of said opposite type of signals are impressed upon said parallel circuit to said relay unit, the input of each pulse-controlled device of each bank being selectively connected in parallel with one input of a pulse-controlled device in each of the other banks, and means for selectively applying input pulses to each set of parallel connected inputs.

2. Electrical decoding and work actuating apparatus comprising a plurality of control banks, said banks each comprising an electrically controlled relay unit, first and second types of electric pulse-controlled devices all having their outputs connected in parallel with one another and connected to said relay unit, each pulse-controlled device having an input for receiving an electric pulse signal, means in the first type of said pulse-controlled device for supplying a de-energizing signal to said relay unit upon application of an electric pulse to the input of said device, means in the second type of said pulse-controlled devices for applying an energizing signal to said relay unit upon application of a pulse to the input of said device, said electrically controlled relay unit including means for causing a signal from any of one of said types of device to always override any opposite signals from the other type devices, regardless of how many of said opposite type of signals are impressed upon said parallel circuit to said relay unit, the input of each pulse-controlled device of each bank being selectively connected in parallel with one input of a pulse-controlled device in each of the other banks, and means for selectively applying input pulses to each set of parallel connected inputs, said banks being arranged in pairs with relay unit of one pair being a work controlling relay and the relay of the other pair being a holding relay for said work controlling relay.

3. Electrical decoding and work actuating apparatus comprising a plurality of control banks, said banks each comprising an electrically controlled relay unit each relay unit comprising an electron relay tube and a plate circuit relay, said relay tube having a grid connected through a grid resistor to a plate voltage source and a cathode connected to a lower voltage source rendering the tube normally conducting, said banks also comprising first and second types of electric pulse-controlled circuits each comprising an electron control tube with the plates of the tubes connected in parallel, said parallel connected plates being connected to the cathode of said relay tube through

a plate load resistor of lower resistance than the grid resistor of said relay tube grid, said parallel connected plates also being connected to the grid of said relay tube, circuit means for rendering the control tubes of said first type normally conducting thereby rendering said relay tube non-conducting due to the voltage drop across the control tube plate load resistor that is connected in the cathode circuit of said relay tube, circuit means for rendering the control tubes of the second type normally non-conducting thereby permitting said relay tube to conduct unless it has been cut off, input circuit means for selectively rendering said first type control tubes non-conducting thereby permitting said relay tube to conduct unless it has been cut off, input circuit means for selectively rendering said second type control tubes conducting thereby rendering said relay tube non-conducting due to the voltage drop across the resistance in the plate resistor connected to the cathode circuit of said relay tube, and the input circuit means of each pulse-controlled circuit in each bank being selectively connected in parallel with one input circuit means of the other banks.

4. Electrical decoding and work actuating apparatus, comprising a plurality of control banks, said banks each comprising an electrically controlled relay unit, each relay unit comprising an electron relay tube and a plate circuit relay, circuit means to render said relay tube normally conducting, said banks also comprising first and second types of electric pulse-controlled circuits each comprising an electron control tube with the plates of the tubes connected in parallel, said parallel connected plates being connected to said relay unit tube by circuit means that cuts off said relay tube when any of said control tubes conduct, circuit means for rendering the control tubes of said first type normally conducting thereby rendering said relay tube non-conducting, circuit means for rendering the control tubes of the second type normally non-conducting thereby permitting said relay tube to conduct unless it has been cut off, input circuit means for rendering said first type control tubes non-conducting on receipt of a pulse thereby permitting said relay unit tube to conduct unless it has been cut off, input circuit means for rendering said second type control tubes conducting on receipt of a pulse thereby rendering said relay tube non-conducting, means for selectively applying pulses to or grounding said input circuit means of said control tubes, the control tube plates of said banks being connected in parallel, and the input circuit means of each control tube in each bank being selectively connected in parallel with one input circuit means of each of the other banks.

5. Electrical decoding and work actuating apparatus comprising a plurality of control banks, said banks each comprising an electrically controlled relay unit, each relay unit comprising an electron relay tube and a plate circuit relay, said relay tube having a grid connected through a grid resistor to a plate voltage source and a cathode connected to a lower voltage source rendering the tube normally conducting, said banks also comprising first and second types of electric pulse-controlled circuits each comprising an electron control tube with the plates of the tubes connected in parallel, said parallel connected plates being connected to the grid of said relay tube and to the cathode of said relay tube through a plate load resistor of lower resistance than the grid resistor of said relay tube grid, a connection from said lower voltage source to the grids of the control tubes of said first type to render said tubes normally conducting thereby rendering said relay tube non-conducting due to the voltage drop across the control tube plate load resistor that is connected in the cathode circuit of said relay tube, an electron trigger tube having its plate connected to said lower voltage source through a resistance and a connection from the plate of said trigger tube to the grid of a control tube of the second type, a cathode bias voltage source for the cathode of said trigger tube, a voltage source connected to the grid of said trigger tube to render

said trigger tube normally conducting, the voltage on the grid of said control tube being less than its cathode voltage with said trigger tube conducting thereby rendering the control tube non-conducting and thereby permitting said relay tube to conduct unless it has been cut off, input circuit means for selectively grounding the grids of said first type control tubes and said trigger tubes, said input circuit means of each tube in each bank being

selectively connected in parallel with one input circuit means of each of the other banks.
